UNITED STATES PATENT OFFICE.

EDWARD TEEKEN, OF LOUISVILLE, KENTUCKY.

DEMOUNTABLE WORKBENCH.

Application filed March 21, 1921. Serial No. 454,122.

To all whom it may concern:

Be it known that I, EDWARD TEEKEN, a citizen of the United States, residing at Louisville, county of Jefferson and State of Kentucky, have invented certain new and useful Improved Demountable Workbenches, of which the following is a specification:

This invention relates to work benches and more particularly to a demountable work bench.

The primary object of the invention is to provide a work bench which is of inexpensive construction and which can be quickly and readily disassembled, the various parts being of such size and shape that they can be compactly arranged to occupy a minimum amount of space, and thus be carried in a workman's tool kit.

Another object of the invention is to provide a demountable work bench adapted to be constructed out of standard pipe fittings, pipe and the like.

A further object of the invention is to provide the work bench with a demountable shelf hanger for conveniently supporting a tool shelf preferably at the front end of the bench.

A still further object of the invention is to provide the work bench with means for conveniently and effectively holding the work in position upon the bench.

With these and other objects in view, as will appear as the description proceeds, the invention comprises the various other novel features of construction, combination and arrangement of parts as will more fully appear hereinafter and be pointed out with particularity in the appended claims.

Referring to the drawing:

Figure 1 represents a top plan view of the work bench,

Figure 2 represents a side elevation of the work bench, showing a piece of work in position as indicated by dotted lines,

Figure 3 represents a front end view of the work bench,

Figure 4 represents a rear end view of the work bench, and

Figure 5 is a detail perspective view of the shelf hanger.

Referring more particularly to the drawing, it will be seen that the work bench comprises fittings 1 and 2, each of which is provided with transverse passages for the reception of a horizontal bar or pipe 3. The forward end of the bar 3 is threaded into the

transverse passage of the fitting 1, while the rear end is slidably mounted in the transverse passage of the fitting 2.

Each of the fittings 1 and 2 are provided with divergent portions into which are threaded the upper ends of the legs 4. It will be apparent that the front legs are arranged in a vertical plane while the rear legs are arranged in a plane at an inclination to the plane of the front legs so as to brace the work bench.

The rear fitting 2 with the legs attached thereto is adapted to be adjusted lengthwise of the bar 3 to vary the length of the work bench to accommodate work of different lengths.

A table top 5 is formed integral with or rigidly connected to the front fitting 1 and is provided with holes 6 for the reception of fastening elements 7 whereby a vise or other work holding means 8 may be securely mounted upon it, as indicated by dotted lines in Figure 2.

The rear fitting 2 is provided with work supporting members 9 which in this instance are in the form of bolts threaded into the fitting at an angle to each other to form a crotch in which one end of the work 10 as indicated by dotted lines is adapted to rest.

Arranged at the front end of the work bench and projecting through between its front legs is a shelf 11 supported by a shelf hanger 12 which is detachably supported by the bar 3 and the front legs of the bench. The hanger, per se consists of a vertical rod 13 having a hook 14 formed at its upper end for engagement over the bar 3, while the lower end joins a longitudinally disposed rod 15. This latter rod being joined medially of a transverse rod 16, the ends of which terminate in hooks 17 for engagement around the front legs 4. If desirable the position of the hanger can be changed and repositioned with relation to the rear bench legs.

From the foregoing description, it will be apparent that I have provided a work bench of simple and inexpensive construction, which is designed primarily to be, though not necessarily, constructed of standard pipe and pipe fittings such as are used in plumbing, steam fitting and various other trades, whereby it can be quickly demounted and conveniently arranged in a compact space for carriage in a workman's tool kit.

While I have shown and described the

principal form of my invention, I desire to have it understood that such changes in construction and arrangement of parts may be made when desired as are within the scope 5 of the appended claims.

What I claim as new is:

1. A demountable work bench comprising front and rear fittings, legs detachably connected to each of said fittings, a bar connecting said fittings, a table top rigid with said front fitting adapted to support a vise, and work holding means carried by the said rear fitting.
2. A demountable work bench comprising front and rear fittings, legs detachably connected to each of said fittings, a horizontal bar connecting said fittings, a table top rigid with said front fitting adapted to support a vise, and work supporting members detachably connected to said rear fitting and disposed at an angle to each other to form a work supporting crotch.
3. A demountable work bench comprising front and rear fittings, a horizontal bar having one end detachably connected to said front fitting and the other end slidably mounted in said rear fitting, legs detachably connected to each of said front and rear fittings, a table top rigid upon said front fitting and provided with holes to attach a vise, and work supporting members detachably mounted on said rear fitting and disposed at an angle to each other to form a work supporting crotch.
4. A demountable work bench, comprising front and rear fittings, a horizontal bar connecting said fittings, legs connected to said front and rear fittings, work holding means carried by each of said front and rear fit-

tings, a shelf hanger suspended from said horizontal bar and adapted to be connected to either the front or rear legs, and a shelf for said hanger.

5. A stand of the character described comprising a vise-supporting member, a work holder, said member and holder having depending socketed bosses, supporting legs seating in the sockets of the bosses, said member and holder also having horizontal sockets, and a coupling rod connecting said member and holder in longitudinally spaced relation, said rod seating in the aforesaid horizontal sockets, and the work holder being adjustable on the rod toward and from the vise-supporting member.

6. A stand of the character described comprising a vise-supporting member, a work holder, said member and holder having depending socketed bosses, supporting legs removably seating in the sockets of the bosses, said member and holder also having horizontal sockets, and a coupling rod connecting said member and holder in longitudinally spaced relation, said rod removably seating in the aforesaid horizontal sockets, and the work holder being adjustable on the rod toward and from the vise-supporting member.

7. A stand of the character described comprising a vise-supporting member, a work holder, a coupling rod connecting said member and holder in longitudinally spaced relation, and on which rod the work holder is adjustable toward and from the vise-supporting member, and supporting legs for said member and holder.

EDWARD TEEKEN.
